MINIATURE POWER-DRIVEN SEWING
MACHINE

David A. Merson, Great Neck, N. Y., and Sidney R. Bell, Stamford, Conn., assignors to Irving J. Moritt, Brooklyn, N. Y.

Application December 12, 1946, Serial No. 715,860

13 Claims. (Cl. 112—169)

1

This invention relates to sewing machines, and more particularly to a miniature lockstitch sewing machine which may, if desired, be held in one hand while being operated.

The primary object of the present invention is to provide a lockstitch sewing machine so small and light that it may be held in one hand while being operated, and so portable that it may be carried in a lady's luggage during trips. It may be moved to the work instead of moving the work to the machine, where the work is relatively large or for some other reason is not conveniently movable.

Some features of the present invention, such as the work feed mechanism and thread take-up mechanism, are disclosed and claimed in our co-pending application Serial Number 714,792, filed December 7, 1946. However, in the present case the sewing machine, although tiny and light in weight, is power-driven instead of being driven manually, as in our co-pending application. In accordance with the present invention, the sewing mechanism is provided with a handle which may be held in one hand and by which the entire machine may be supported, and the electric motor for driving the sewing mechanism is housed within the aforesaid handle.

In accordance with another feature of the invention, a motor-controlling switch button is provided which is accessible to a finger of the hand holding the aforesaid handle, so that the machine may be operated in short runs by momentary pressure on the button.

Another object of the invention is to provide smoothly running cam and cam follower mechanism driven by the aforesaid motor for driving both the needle and the shuttle in properly timed relation.

Still another object of the invention is to provide power-driven winding mechanism for winding thread on a bobbin. As will later appear, this is done by using the main spool support for this additional purpose.

To accomplish the foregoing general objects, and other more specific objects which will hereinafter appear, our invention resides in the miniature lockstitch sewing machine elements and their relation one to the other, as are hereinafter more particularly described in the following specification. The specification is accompanied by drawings, in which:

Fig. 1 is a partially sectioned elevation of a sewing machine embodying features of our invention;

Fig. 2 is a horizontal section taken approxi-

2

mately in the plane of the line 2—2 of Fig. 1;

Fig. 3 is a vertical section taken approximately in the plane of the line 3—3 of Fig. 2;

Fig. 4 is a horizontal section taken approximately in the plane of the line 4—4 of Fig. 3;

Fig. 5 is a plan view of the shuttle with the bobbin positioned therein;

Fig. 6 is a partially sectioned end elevation of the sewing machine;

Fig. 7 is a fragmentary view similar to Fig. 6, but showing the work feed dog in retracted position;

Fig. 8 is a vertical section taken approximately in the plane of the line 8—8 of Fig. 1;

Fig. 9 is a section through a part of the control switch for the motor, said section being taken approximately in the plane of the line 9—9 of Fig. 8; and

Fig. 10 is a time diagram showing the action of the cams employed in the mechanism.

Referring to the drawings, and more particularly to Fig. 1, the miniature hand-holdable lockstitch sewing machine there shown is very small, the body of the machine exclusive of the handle being less than five inches in length, and the entire machine including the handle or motor housing, being less than eight inches long. The machine comprises a needle 12 receiving a first thread 14, a shuttle 16 having a bobbin 18 for supplying a second thread, and a handle 20 which houses an electric motor for driving the machine. There is a thread take-up mechanism, part of which is shown at 22 in Fig. 1, and all of which is shown in Fig. 3. There is also work feed mechanism including a work feed dog 24 (Fig. 1). The switch button 26 is accessible to a finger of the hand holding the handle 20. This switch button controls the operation of the motor, either by pressure for short runs, or by sliding movement for long runs. Power is supplied to the motor through a conventional flexible cord 28 having a female connector 30 detachably plugged into the end of the handle, as is better shown in Fig. 3.

The machine has a relatively flat bottom and therefore may be rested on a table for support, instead of being held by the hand which operates the machine. If desired, it may even be clamped on a table as by means of a removable clamp (not shown) generally resembling a C-clamp, but having a top arm which is of dovetail section and adapted to be slidably received in a mating dovetail slot 32 in the bottom of the machine.

Needle bar drive

Referring to Fig. 3 of the drawing, the motor shaft 34 is carried in bearings 36 and 38 which are preferably anti-friction bearings of the self-lubricating type. Bearing 36 is received in a part of the main housing 40 of the machine. This housing is preferably die-cast out of one of the light-weight metals such as aluminum or magnesium. Bearing 38 is supported in a support 42 extending diametrically across the outer portion 44 of the motor housing; this being a separate casting which is fitted to the handle portion 20 of the main housing 40, the parts being held in assembled relation by tie-rods 46 which have threaded ends screwed into housing 40. The armature 48 with armature windings 50 connected to commutator 52 are all carried on the motor shaft 34 in conventional fashion. The laminated ferrous metal for the field is fitted into the casing 20 with a force fit, and the field windings 54 are added in the usual manner. The brushes for engaging the commutator are preferably carbon brushes of rectangular cross-section received in appropriate guides disposed diametrically on opposite sides of the commutator, the brushes being urged inwardly by small helical compression springs held in place by screws, one of which is shown at 55 in Fig. 1. The motor may be conventional, and it is therefore believed that a more detailed description is unnecessary for the present purpose.

The construction of the switch 26 is illustrated in Figs. 8 and 9 of the drawings. Referring thereto, it will be seen that the inner end 140 of button 26 bears against a movable contact 142 disposed collaterally of a stationary contact 144. A bifurcated spring 146 is provided for mechanical reasons, this being received in slots on opposite sides of button 26. The spring 146 holds the button 26 against escape, and also urges the button outward to the position shown in Fig. 8, so that the switch contacts are normally open. However, pressure on button 26 moves contact 142 against contact 144, thus closing the circuit and energizing the motor. If desired, the switch may be kept closed, this being done by sliding the button downwardly, in which case the sloping end 140 of the button acts as a cam against the movable contact 142. However, in most cases the button is used for momentary contact, the machine being operated only so long as the button is pressed.

Reverting to Fig. 3, the forward end of the motor shaft 34 carries a pinion 56 which meshes with a gear 58 secured to a bevel pinion 60, which in turn is carried on a stud 62 secured to a bearing pedestal 64 screwed to the base 66 of the machine (see Fig. 4).

Pinion 60 meshes with a bevel gear 70 fastened by means of screws to the lower end of a cylindrical cam 72. This is rotatable on a shaft or pin 74 the lower end of which is received in a bearing 76 in the base 66, and the upper end of which is received in a bearing 78 in the housing 40.

The needle 12 is carried at the forward end of a needle bar 80, the rear or base end of which is enlarged to form a cross-head 82 which is vertically reciprocable on guides or ways 84. The ways 84 (Fig. 2) are secured to the cast housing by means of screws 86, and are preferably made of "Oilite" or equivalent self-lubricating bearing metal. A cam follower roller 88

is received in a cam track 90 in cylindrical cam 72. It will be evident that the cross-head, needle bar and needle are reciprocated vertically as the cylindrical cam is rotated by the motor.

The shape of the cam track is such as to move the needle to lowermost position, to then raise the needle slightly to form a loop of thread, to then dwell briefly to afford time for the shuttle to engage said loop, and to then raise the needle. The timing of the particular machine here illustrated is shown in Fig. 10, in which the curve A corresponds to or is a development of the surface of the cylindrical cam. It will be seen that the needle is lowered in about 135° rotation of the cam; raised about an eighth of inch during the next 35°; dwells for approximately 90°; and is raised to initial position in the next 90°. There is a short dwell in top position.

The shuttle drive

Referring to Fig. 1, the shuttle 16 rests on a shuttle carrier which is connected to and rotated by a pinion 92. Referring now to Fig. 4, it will be seen that pinion 92 meshes with a rack 94 which is guided in a track 96. The rear end of rack 94 is provided with a cam follower roller 98 received in a cam groove 100. Referring now to Fig. 3, the cam groove 100 may be formed in the bottom face of the bevel gear 70 previously referred to. It will thus be evident that the shuttle is oscillated as the cylindrical cam is rotated. The cam shape is developed in Fig. 10, and is shown as curve B. The descending portion of curve B corresponds to return movement of the shuttle, while the ascending portion corresponds to forward movement of the shuttle, such that the hook of the shuttle engages the loop of thread formed by the needle when it rises slightly from lowermost position. The needle dwells from about 170° to 260°, and during this dwell period the shuttle catches the loop and draws it around itself.

The shuttle is shown in somewhat greater detail in Fig. 5, but probably requires no detailed description because it may be and preferably is conventional. It includes a hook 102 which engages the loop formed by partial upward movement of the needle as previously described, the needle working in a needle hole shown at 104. The shuttle is oscillated approximately 250°, this being accomplished by the pinion and rack mechanism previously described.

The bobbin is best shown at 18 (Fig. 5), and it will be understood that the bottom thread comes from the bobbin 18 past a spring tensioning device in the shuttle, then through a hole in the shuttle, and finally through the regular needle hole located directly above the hole 104, said needle hole being formed in a needle plate which is slidably removable from above the shuttle when the bobbin is to be re-wound. The needle plate is shown in position at 106 in Fig. 1, but is assumed removed in Fig. 5.

The shuttle 16 rests loosely on a shuttle carrier in such a manner that a loop of the upper thread in 65 may be passed entirely around the shuttle when the hook 102 engages the loop and turns another 180°. As the shuttle turns still further past dead center, the loop escapes from the open side of the hook on the opposite side of the shuttle. This 70 interengages the upper and lower threads. The large slack loop is then tightened both by the thread take-up mechanism, and by raising of the needle itself. The shuttle turns back (clockwise in Fig. 5) to initial position preparatory to making the next stitch, and since in the meantime the

cloth being sewn is fed a short distance by the work feed dog, the next stitch will in each case be spaced from the previous stitch.

The thread take-up

Referring to Fig. 3 of the drawings, the upper thread is taken from a spool 110 and is run through an eye 112 and a thread tensioning device 114, this being of conventional type employing two discs held together by a spring the tensioning of which may be adjusted by means of a knob 116. From the thread tensioning device the thread is run through an eye 118 to a hole at the end 120 of the thread take-up arm 22. The thread is then led down to an eye 122 and thence to the eye of the needle 12, the thread being passed from the outside toward the inside of the needle, as is better shown in Fig. 1.

The thread take-up arm 22 is operated by direct connection to the needle bar 80. Specifically, the arm 22 is pivoted at 124. A link 126 is connected to the cross-head of the needle bar 80 at 128, and is connected to the arm 22 at 130. Actually, a pair of links 126 may be used, one on each side of the arm 22, as is best shown in Fig. 6, but for purposes of description, they may be considered a single link. There is a lost-motion connection between the needle bar 80 and the arm 22, this being provided by slotting the end of link 126, as is shown at 132. This lost-motion connection is provided because the preferred timing of the take-up arm 22 is not the same as that of the needle bar 80. With the lost-motion connection, the operation is less critical in timing because there is a period of maximum slack when the thread take-up arm is in lowermost position, instead of only an instant of maximum slack. This lowermost position of the take-up arm is shown in broken lines at 22' (Fig. 3), and corresponds to lowering of the needle bar 80 to the broken-line position 80'. The maximum slack is maintained over a time period corresponding generally to the time when the shuttle draws the loop of thread diametrically around itself. Thereafter the thread take-up begins to tighten the loop to small size.

Work feed mechanism

The work feed mechanism is best shown in Figs. 2, 6 and 7. Referring thereto, the work is fed by a serrated feed dog 24 which is bifurcated to straddle the needle. The feed dog is oscillated about a pivot 152 by a rod 154 which extends vertically upwardly to the needle bar 80. In Fig. 6, the needle bar is shown in elevated position, it moving against a collar 156 on the upper end of rod 154, thereby pulling the rod upwardly and so moving the feed dog 24 in work feeding direction. This takes place while the needle 12 is raised, so that the work is freed for forward feed movement. In Fig. 7, the needle bar 80 is shown in lowermost position, bearing against an enlargement 158 at the bottom of rod 154, thus oscillating the feed dog 24 in rearward direction, this taking place while the needle 12 is down through the work, thereby holding the work against rearward movement. The rod 154 is a lost-motion connection such that much of the motion of the needle bar does not affect the feed dog. The movement of the feed dog and consequently the length of the stitch, may be controlled by a bushing 160 threadedly received in an ear 162 projecting sidewardly from the needle bar 80. When the bushing is screwed upwardly, the stitch is lengthened, and when the bushing is screwed downwardly, the stitch is shortened.

The work feed mechanism preferably includes means to relieve the pressure of the feed dog on the work during its return movement. For this purpose, the pivot 152 (Fig. 2) of the feed dog is preferably carried on a dog-supporting rocker arm 164 pivoted at 166 on a bracket 168 which carries the entire feed mechanism. Rocker 164 is permitted a slight up and down movement, this being limited by appropriate means which in the present case consists of an inturned end 170 which bears against the outside of bracket 168 when the rocker is elevated slightly, as shown in Fig. 7. The lower end of rod 154 is connected to a dog operating lever 172 (Fig. 2) pivoted directly on bracket 168 at 174. In Fig. 2 it will be seen that although the pivot 152 of the feed dog is substantially in alignment with the pivot 174 of lever 172, they are not a common pin, the pivot 174 being immovable on bracket 168, and the pin 152 being free to rise or fall with the rocker 164. Lever 172 rigidly carries a pin 176 which engages a slot 178 in the end of the feed dog.

Referring to Fig. 6, downward movement of pin 176 tends to move the rocker 164 and the feed dog 24 downward, and after engagement of the work, so that the dog can no longer move downwardly, it is necessarily turned about its pivot 152. Referring next to Fig. 7, upward movement of the pin 176 tends to move the rocker 164 upwardly, thus elevating the feed dog 24 from the work until the rocker can no longer rise, its motion being limited by the stop 170. Thereafter the feed dog is necessarily swung about its pivot 152. If desired, a small leaf spring 180, best shown in Figs. 1 and 2, may be provided to normally urge the rocker 164 downwardly, thereby assuring a bias in favor of tight frictional feed of the fabric being sewn.

The entire feed mechanism so far described is carried on bracket 168, which is itself bodily movable upwardly. This movement is desirable when starting a new piece of work in the machine, or when removing work from the machine, or when threading the needle. The base end of bracket 168 forms a cross-head 182 (Figs. 2 and 6), which is slidable on a dovetail sectioned guide 184. A small handle or finger-piece 186 may be provided to raise or lower bracket 168, and in Figs. 1 and 2 it will be seen that this finger-piece is pivoted at 188, and is connected to a pin 190 projecting from the cross-head 182. Pin 190 is received in a slot in the finger-piece, and it will be evident that by raising or swinging the finger-piece in clockwise direction, as seen in Fig. 1, the bracket 168 and with it the entire feed mechanism is bodily raised. This upward motion is permitted by the slidable relation of rod 154 in bushing 160.

The finger-piece may be designed to lock the bracket in down position, but this is not essential because of the overhung nature of the bracket, for any upward pressure at the end locks the cross-head on the guide.

The bobbin winder

Referring to Fig. 1, it will be seen that the upper end 192 of the spool support rod 194 is fluted, and thereby adapted to frictionally receive the bobbin 18 of the shuttle 16 previously referred to. The rod 194 may be rotated by the motor, and thus thread may be taken from the spool and fed directly to the bobbin until the bobbin has been wound. The spool, of course, is loose on support rod 194, and is not affected by the rotation of the rod.

Referring now to Fig. 3 of the drawings, it will be seen that rod 194 is rotatable in a bearing 196 and is held against axial movement by a collar 198 above bearing 196, and a head or wheel 200 below bearing 196. A lever 202 is oscillatable about the bushing 196 and rod 194 (see Fig. 2) previously referred to. It is normally urged in clockwise direction to the inoperative position shown in Fig. 2, by a leaf spring 204. The end 206 of lever 202 is serrated and projects through a slot 208 in the housing wall. Lever 202 carries an idler wheel 210 which bears against the enlarged head 200 at the bottom of spool support rod 194. By pressing the serrated end 206 of lever 202 in counter-clockwise direction, the intermediate or idler wheel 210 is pressed against the periphery of the cylindrical cam 72 at its upper end. The spool support rod is then rotated by the motor, which is convenient for winding the bobbin. At other times, the intermediate or idler wheel 210 is disengaged from the cylindrical cam, and the spool support rod remains stationary. It will be understood that the intermediate wheel 210 is preferably made of rubber or fibre or equivalent frictional material.

Operation

When first setting up the machine, some of the thread from the spool 110 is wound on the bobbin 18, the bobbin at this time being placed at the top end 192 of the rod 194, the motor button 26 being depressed, and the lever 202 being shifted by means of its serrated end 206. The wound bobbin is then placed in the shuttle, and the thread is appropriately threaded from the bobbin, in conventional fashion, ending upwardly through the needle hole in the needle plate. The upper thread is taken from the spool and threaded as previously described. The work feed mechanism is elevated, the work inserted in the machine, and the feed mechanism lowered, following which the motor control button 26 is pressed until the line of stitching has been carried as far as desired.

The detailed operation of the machine will probably be evident from the description already given, the needle coming down to lowermost position and thus bring the upper thread through the work, the needle then rising a little to form a loop beneath the work, whereupon the shuttle oscillates, its hook catching the loop and expanding the loop around itself. The necessary thread is provided by lowering of the thread take-up arm. When the loop is carried more than half-way around the shuttle, it slides from the open end of the hook around the opposite side of the shuttle, and raising of the needle and thread take-up draws the loop tight, it having meanwhile been interlocked with the bobbin thread of the shuttle. The shuttle turns back to initial position. After the needle has left the work and near the top of its upward stroke, the feed dog moves the fabric ahead, so that when the needle again descends it enters a new point on the fabric.

If a small amount of sewing is to be performed, the machine may be held in one hand or rested loosely on a table. If a great amount of sewing is to be performed, the machine may be clamped near the edge of a table by means of an appropriate C-clamp having a dovetail top. If a little stitching must be done on a large body of fabric hanging in place, or which for any reason it would be inconvenient to move to the sewing machine, the machine may be carried to the work and there operated.

It is believed that the construction and opera-

tion of our improved miniature, power-operated, hand-holdable sewing machine will be apparent from the foregoing detailed description thereof. It will also be apparent that while we have shown and described our invention in a preferred form, changes may be made in the structure disclosed, without departing from the spirit of the invention as sought to be defined in the following claims.

We claim:

1. A miniature lockstitch sewing machine comprising a sewing machine body, a driving motor for the sewing machine, a needle bar and a vertical needle receiving an upper thread and arranged for vertical movement, a shuttle having a bobbin for supplying a second thread to be interlocked with the first thread, a vertical cam shaft housed in the body of said machine, reduction gearing connecting the driving motor to said cam shaft, the upper part of said shaft having a cam for vertically reciprocating the needle, the lower end of said shaft having a radial cam, a pinion on the aforesaid shuttle, a gear rack meshing with said pinion, and a cam follower on said gear rack engaging the aforesaid radial cam for reciprocating said gear rack.
2. A miniature lockstitch sewing machine comprising a sewing machine body, a driving motor for the sewing machine, a needle bar and a vertical needle receiving an upper thread and arranged for vertical movement, a shuttle having a bobbin for supplying a second thread to be interlocked with the first thread, a vertical cam shaft housed in the body of said machine and reduction gearing connecting the driving motor to said cam shaft, the upper part of said shaft having a cylindrical cam with a helical type cam groove for vertically reciprocating the needle, the lower end of said shaft having a face cam with a radial cam groove, a pinion on the aforesaid shuttle for oscillating the same, a gear rack meshing with said pinion and slidable longitudinally of the machine, and a cam follower on said gear rack engaging the aforesaid radial cam groove for reciprocating said gear rack.
3. A miniature light-weight hand-holdable lockstitch sewing machine mechanism, said mechanism including a needle receiving a first thread, a shuttle having a bobbin for supplying a second thread, a handle projecting from said mechanism, an electric driving motor for said mechanism housed in said handle, means driven by said motor for reciprocating the needle through the work and toward and from the shuttle, and means driven by said motor for oscillating the shuttle to interlock the threads, said means including a vertical cam shaft in the body of the machine, reduction gearing connecting said motor to said shaft, a radial cam at the lower end of the shaft near the bottom of the machine, a gear on the shuttle, a rack meshing with said gear, and a cam follower engaging said cam for reciprocating said rack.
4. A miniature light-weight hand-holdable lockstitch sewing machine mechanism, said mechanism including a needle receiving a first thread, a thread take-up means for said first thread, a shuttle having a bobbin for supplying a second thread, a work feed dog, a handle projecting from said mechanism, an electric driving motor for said mechanism housed in said handle, means driven by said motor for reciprocating the needle through the work and toward and from the shuttle, means driven by said motor to operate the feed dog to cause a relative movement of the machine and the work being sewn, and means driven by said motor for oscillating the shuttle

to interlock the threads, said means including a vertical cam shaft in the body of the machine, reduction gearing connecting said motor to said shaft, a radial cam at the lower end of the shaft near the bottom of the machine, a gear on the shuttle, a rack meshing with said gear, and a cam follower engaging said cam for reciprocating said rack.

5. A miniature light-weight lockstitch sewing machine mechanism, said mechanism including a needle receiving a first thread, a shuttle having a bobbin for supplying a second thread, a handle projecting from said mechanism, an electric driving motor for said mechanism housed in said handle, means driven by said motor for oscillating the shuttle to interlock the threads, a normally horizontal overhung needle bar extending longitudinally of the machine and replacing the arm of a conventional sewing machine, the aforesaid needle being carried in a normally vertical position at the free end of said needle bar, stationary guides or ways slidably receiving the opposite end of said horizontal needle bar for vertical movement, and cam and cam follower mechanism driven by said electric motor for vertically reciprocating the needle bar and thereby reciprocating the needle through the work and toward and from the shuttle.

6. A miniature light-weight lockstitch sewing machine mechanism, said mechanism including a needle receiving a first thread, thread take-up means for said first thread, a shuttle having a bobbin for supplying a second thread, a work feed dog, a handle projecting from said mechanism, an electric driving motor for said mechanism housed in said handle, means driven by said motor for oscillating the shuttle to interlock the threads, means driven by said motor to operate the feed dog to cause a relative movement of the machine and the work being sewn, a normally horizontal overhung needle bar extending longitudinally of the machine and replacing the arm of a conventional sewing machine, the aforesaid needle being carried in a normally vertical position at the free end of said needle bar, stationary guides or ways slidably receiving the opposite end of said horizontal needle bar for vertical movement, a cam follower carried by said needle bar, and a cylindrical cam driven by said electric motor for vertically reciprocating the cam follower and needle bar, and thereby reciprocating the needle through the work and toward and from the shuttle.

7. A lockstitch sewing machine mechanism utilizing a spool of first thread and a bobbin for a second thread, and including a needle receiving the first thread, thread take-up means for said first thread, a shuttle having the aforesaid bobbin for supplying the second thread, a work feed dog, and an electric driving motor for driving said mechanism, a vertical spool-retaining shaft for loosely receiving a main spool of thread, said shaft being longer than the usual spool and having an upwardly extending free end projecting beyond the spool, the said free end of said shaft being fluted to frictionally receive the bobbin, bearing means rotatably mounting the shaft, and means for operatively connecting the driving motor and the spool-retaining shaft when it is desired to wind thread on the bobbin.

8. A miniature light-weight lockstitch sewing machine mechanism, said mechanism including a needle receiving a first thread, a shuttle having a bobbin for supplying a second thread, a handle projecting from said mechanism, an electric driv-

ing motor for said mechanism housed in said handle, means driven by said motor for reciprocating the needle through the work and toward and from the shuttle, and means driven by said motor for oscillating the shuttle to interlock the threads, a spool-retaining shaft for loosely receiving a main spool of thread, said shaft being longer than the usual spool and having an upwardly extending free end projecting beyond the spool, said free end of said shaft being fluted to frictionally receive the bobbin, bearing means rotatably mounting the shaft, and optionally usable means for operatively connecting the driving motor and the spool-retaining shaft when it is desired to wind thread on the bobbin.

9. A miniature light-weight lockstitch sewing machine mechanism, said mechanism including a needle receiving a first thread, thread take-up means for said first thread, a shuttle having a bobbin for supplying a second thread, a work feed dog, a handle projecting from said mechanism, an electric driving motor for said mechanism housed in said handle, means driven by said motor for reciprocating the needle through the work and toward and from the shuttle, means driven by said motor for oscillating the shuttle to interlock the threads, and means driven by said motor to operate the feed dog to cause a relative movement of the machine and the work being sewn, a vertical spool-retaining shaft for loosely receiving a main spool of thread, said shaft being longer than the usual spool and having an upwardly extending free end projecting beyond the spool, the free upper end of said shaft being fluted to frictionally receive the bobbin, bearing means rotatably mounting the shaft, and a friction wheel movably mounted for operatively connecting the driving motor and the spool-retaining shaft when it is desired to wind thread on the bobbin.

10. A miniature light-weight lockstitch sewing machine mechanism, said mechanism including a needle receiving a first thread, a shuttle having a bobbin for supplying a second thread, a handle projecting from said mechanism, an electric driving motor for said mechanism housed in said handle, a motor-controlling switch button accessible to a finger of a hand holding the aforesaid handle, means driven by said motor for reciprocating the needle through the work and toward and from the shuttle, and means driven by said motor for oscillating the shuttle to interlock the threads, a spool-retaining shaft for loosely receiving a main spool of thread, said shaft being longer than the usual spool and having an upwardly extending free end projecting beyond the spool, said free end of said shaft being arranged to frictionally detachably receive the bobbin, bearing means rotatably mounting the shaft, and optionally usable means for operatively connecting the driving motor and the spool-retaining shaft when it is desired to wind thread on the bobbin.

11. A miniature light-weight lockstitch sewing machine mechanism, said mechanism including a needle receiving a first thread, a shuttle having a bobbin for supplying a second thread, a handle projecting from said mechanism, an electric driving motor for said mechanism housed in said handle, a normally horizontal overhung needle bar extending longitudinally of the machine and replacing the arm of a conventional sewing machine, the foresaid needle being carried in a normally vertical position at the free end of said needle bar, stationary guides or ways slidably

11

receiving the opposite or rear end of said horizontal needle bar for vertical movement, the body of said machine having a vertical cam shaft, and reduction gearing for connecting the motor to said shaft, the upper part of said shaft having a cam for vertically reciprocating the needle bar and thereby reciprocating the needle through the work and toward and from the shuttle, the lower part of said shaft having a radial cam, a gear on the aforesaid shuttle, a rack meshing with the gear, and a cam follower engaging said radial cam for reciprocating said rack longitudinally of the machine and thereby oscillating the shuttle to interlock the threads.

12. A miniature light-weight lockstitch sewing machine mechanism, said mechanism including a needle receiving a first thread, a shuttle having a bobbin for supplying a second thread, a work feed dog, a handle projecting from said mechanism, an electric driving motor for said mechanism housed in said handle, means driven by said motor to operate the feed dog to cause a relative movement of the machine and the work being sewn, a normally horizontal overhung needle bar extending longitudinally of the machine and replacing the arm of a conventional sewing machine, the aforesaid needle being carried in a normally vertical position at the free end of said needle bar, stationary guides or ways slidably receiving the opposite or rear end of said horizontal needle bar for vertical movement, the body of said machine having a vertical cam shaft, and reduction gearing for connecting the motor to said shaft, the upper part of said shaft having a cam for vertically reciprocating the needle bar and thereby reciprocating the needle through the work and toward and from the shuttle, the lower part of said shaft having a radial cam, a gear on the aforesaid shuttle, a rack meshing with the gear, and a cam follower engaging said radial cam for reciprocating said rack longitudinally of the machine and thereby oscillating the shuttle to interlock the threads.

12

13. A miniature light-weight lockstitch sewing machine mechanism, said mechanism including a needle receiving a first thread, a shuttle having a bobbin for supplying a second thread, a handle projecting from said mechanism, an electric driving motor for said mechanism housed in said handle, a motor-controlling switch button accessible to a finger of a hand holding the aforesaid handle, a normally horizontal overhung needle bar extending longitudinally of the machine and replacing the arm of a conventional sewing machine, the aforesaid needle being carried in a normally vertical position at the free end of said needle bar, stationary guides or ways slidably receiving the opposite or rear end of said horizontal needle bar for vertical movement, the body of said machine having a vertical cam shaft, and reduction gearing for connecting the motor to said shaft, the upper part of said shaft having a cam for vertically reciprocating the needle bar and thereby reciprocating the needle through the work and toward and from the shuttle, the lower part of said shaft having a radial cam, a gear on the aforesaid shuttle, a rack meshing with the gear, and a cam follower engaging said radial cam for reciprocating said rack longitudinally of the machine and thereby oscillating the shuttle to interlock the threads.
